UNITED STATES PATENT OFFICE.

THEODORE URBANSKI, OF HOLLAND, OHIO.

WOOD-SAWING MACHINE.

1,266,355.

Specification of Letters Patent. Patented May 14, 1918.

Application filed July 19, 1916. Serial No. 110,108.

To all whom it may concern:

Be it known that I, THEODORE URBANSKI, a citizen of the United States, residing at Holland, in the county of Lucas and State 5 of Ohio, have invented new and useful Improvements in Wood-Sawing Machines, of which the following is a specification.

This invention relates to improvements in wood sawing machines and has particular 10 application to a machine whereby a cross cut saw may be operated conveniently by one operator.

In carrying out the present invention, it 15 is my purpose to provide a wood sawing machine whereby a single operator may manipulate a cross cut saw conveniently and with a minimum effort and wherein the saw will be held in engagement with the timber under pressure at all times, thereby enabling 20 the saw to bite into the wood.

It is also my purpose to provide a machine 25 of the class described wherein the supports will remain stationary and rigid in the operation of the saw, whereby preventing lateral movement of the saw and creeping of the supports in the operation of the saw.

With the above and other objects in view, the invention consists in the construction, combination and arrangement of parts here- 30 after set forth in and falling within the scope of the claims.

In the accompanying drawings:

Figure 1 is a view in side elevation of a 35 wood sawing machine constructed in accordance with the present invention, the same being shown in use.

Fig. 2 is a top plan view of the same.

Fig. 3 is a vertical sectional view there- 40 through, on the line 3—3 of Fig. 1.

Fig. 4 is a horizontal sectional view on the line 4—4 of Fig. 1.

Fig. 5 is a perspective view of the holding dogs.

Referring now to the drawings in detail, 45 1 designates a base constructed of suitable material and provided with depending prongs 2 adapted to bite into the ground. Uprising from the base 1 is a vertical standard 3 and fastened to the standard 3 adja- 50 cent to the upper end thereof is one end of a horizontal supporting arm 4 adapted to overlie the timber being cut. Secured to the standard 3 adjacent to the upper end thereof is a slotted bracket 5 and mounted in the bracket 5 and capable of vertical adjustment 55 therein is a bolt 6. Pivoted between its

ends upon the bolt 6 is a lever 7 having one end formed to provide a handle 8. Hinged to the other end of the lever 7 is an arm 9 connected to one extremity of a cross cut saw 60 blade 10 and pivotally connected to the other end of the saw blade 10 is one extremity of an arm 11 having the other end hinged to one end of an arm 12. This arm 12 is pivotally connected to the outer end of the supporting arm 4 and bearing upon the arm 12 is a spring 13. Pivotally mounted upon the arm 4 adjacent to the standard 3 is a spring 65 operated arm 14 provided with a roller 15 engaging the upper edge of the saw blade. 70 These spring operated arms 12 and 14 exert downward pressure on the saw blade 10 to hold the latter in engagement with the timber. 16 indicates holding dogs pivoted upon the arm 4 and designed to bite into the timber 75 to prevent longitudinal movement of the arm 4 across the timber. Secured to the supporting arm 4 is a guide 17 that engages the saw 10 in the initial operation thereof to hold the blade straight. 80

The supporting arm 4 is adjustably secured to the standard 3 by a bolt 18 which extends through the arm and through a vertical slot 19 formed in the standard. The standard is counter sunk on one side adjacent the slot to receive the head 20 of the bolt to hold the latter from turning, thus making it possible to tighten the nut 21 so as to hold the arm 4 in any adjusted vertical position. 90

The bolt 6 which pivotally secures the lever 7 to the bracket 5 extends through a vertical slot 22 in the bracket and carries a nut 23 which may be tightened to hold the lever in any adjusted position. It will be 95 noted that this manner of individually connecting the arms 4 and lever 7 to the standard 3 allows for independent adjustment which is often advantageous, as for instance, when it is desirable to change the position of the arm 4 to better accommodate itself to a log and still leave the operating lever in its original adjusted position. 100

In practice, the dogs 16 are engaged with the work and the saw blade held to the work under the action of the spring arms 12 and 14. The bolt 6 carrying the lever 7 is now adjusted in the bracket 5 to the desired position and the lever 7 swung back and forth to reciprocate the saw blade 10, thereby cutting the timber. 110

A prong 24 is pivotally secured as at 25

to an end plate 26 fixed to the upper terminal of the standard 3 and this prong may, as will be clearly understood, be swung into different positions with respect to the standard 5 so as to assist in supporting the latter by engaging the ground or other support at certain times. The dogs 16 are preferably held in gripping position by means of a spring 16' interposed between the dogs and 10 connected thereto, as clearly illustrated in Fig. 5 of the drawings.

The coil spring 16' encircles the rods 27 and 28 at their overlapping portions and engages respectively the laterally turned 15 ends of the rods. The rod 27 extends through one of the prongs 16 and is secured in fixed relation thereto by a nut 29 whereas the other rod is enlarged adjacent 20 its outer terminal and formed along one edge with ratchet teeth 30 which are engaged by a spring pressed pawl 31 pivoted to the other dog. The pawl provides for an adjustment to properly accommodate the dogs to various sizes of tree trunks.

25 I claim:

1. In a wood sawing machine, a standard, an arm, means for adjusting the arm vertically on the standard while holding the same in a horizontal plane, a lever having 30 its pivotal point vertically adjustable on said standard, said arm and lever being adjustable independently of one another, and a saw operatively connected to said arm and lever.

35 2. In a wood sawing machine, having a longitudinal slot formed therein, a bolt ex-

tending through said slot and adjustable therein, an arm secured at one end to said bolt, a bracket fixed to said standard and formed with a longitudinal slot running 40 lengthwise of the standard, a bolt extending through the slot in the bracket and adjustable to different positions, a lever pivoted intermediate its ends on said bolt, and a saw operatively connected to the arm and lever, 45 the arm and lever being adjustable independently of each other.

3. In a sawing machine, an arm adapted to overlie a tree to be sawed, a pair of dogs pivoted at one end and adapted to engage 50 a tree, a rod fixed to one of the dogs and extending toward the other, a second rod slideable through one of said dogs and extending toward the other, said rods overlapping at their inner ends, a coil spring encircling the 55 overlapping portions, the rods being extended laterally at their inner ends to engage said spring, the slidably mounted rod being provided on its outer end with teeth and a pawl carried by one of the dogs to 60 engage the teeth.

4. In a sawing machine, an arm, a pair of dogs pivoted to said arm, a rod secured to one of the dogs and extending toward the other, a second rod slideable through the 65 other dog, said rods having their inner portions overlapping, spring means connecting said overlapped portions and means for adjustably connecting the slidably mounted rod to its dog.

70 In testimony whereof I affix my signature.
THEODORE URBANSKI.
